UNITED STATES PATENT OFFICE.

JOHN H. MCKELVEY, OF KIRKWOOD, AND CHARLES F. RYAN, OF ST. LOUIS, MISSOURI.

APPARATUS FOR MAKING PLATE-GLASS.

1,274,916.

Specification of Letters Patent.

Patented Aug. 6, 1918.

Application filed June 7, 1915. Serial No. 32,599.

To all whom it may concern:

Be it known that we, JOHN H. MCKELVEY, a citizen of the United States, residing at Kirkwood, in the county of St. Louis and State of Missouri, and CHARLES F. RYAN, a citizen of the United States, residing at St. Louis, State of Missouri, have invented certain new and useful Improvements in Apparatus for Making Plate-Glass, of which the following is a specification.

This invention relates to improvements in apparatus for making plate glass. The main object of this invention is to provide an apparatus to enable us to carry out the process set forth in our co-pending application Serial No. 20,861 of such character that the batch may be continuously introduced into a melting furnace and the melting carried on continuously in contradistinction to the processes at present in use, in which melting pots or flasks are employed. The use of these flasks requires that the batch therein be replenished from time to time until the molten glass nears the capacity of each flask. This requires considerable waste in time and labor and is an inefficient operation at best. Another objection to the flask type of process is that the flasks quite frequently break, causing a loss of their contents and requiring shutting down of the furnaces from time to time. Furthermore, the present day methods of handling and conveying the flasks from the melting furnace to the rolling table are laborious and result in much waste of time, material, etc.

By the use of our apparatus we are enabled to continuously melt the batch and maintain a constant supply of the molten glass available. Furthermore, we provide a teeming chamber in connection with our apparatus into which a desired amount of the molten glass may be directly drawn from the tank furnace and in conjunction with this teeming chamber we provide a rolling table movable to and from beneath the teeming chamber. We further provide means to deposit the molten glass from the teeming chamber directly adjacent and beneath the roller. We still further provide means for actuating the rolling table, the roller, and means to remove the rolled plate from the table into the leer. These and other objects and ends we obtain by the use of the appa-

ratus described below and shown in the accompanying drawings, in which:

Figure 1 is a horizontal section of our improved apparatus;

Fig. 2 is a vertical section of one of the regenerative sections;

Fig. 3 is a vertical section through the pouring end of the tank furnace and showing the rolling table in elevation;

Fig. 4 is a plan view of the table in position preliminary to rolling plate;

Fig. 5 is a side elevation of the same;

Fig. 6 is an enlarged side elevation of the table and actuating mechanism therefor;

Fig. 7 is an end elevation of the same.

Like numerals refer to like elements throughout the drawings, in which 10 indicates generally the melting furnace comprising the side walls 10^a, end walls 10^b and 10^c, respectively, hearth or floor 10^d composed of suitable refractory blocks or tile, 75 and the top or roof 10^e. Suitable charging openings are provided in the end wall 10^c, the same being indicated by numerals 10^f, see Fig. 1. Adjacent the end wall 10^c and the openings 10^f therethrough, are the platforms 10^g upon which the batch is deposited previous to its introduction into the furnace. When the furnace is in operation sufficient batch is maintained on these platforms to close, or substantially close the openings 10^f through which from time to time the batch may be pushed. Combustion chambers 10^h are provided in each side of the furnace leading through the side walls 10^a, see Figs. 1 and 2. Leading to these combustion openings 10^h are the gas and air ducts 10ⁱ and 10^j, respectively, leading from suitable checker work, generally indicated by numerals 10^k, 10^m. The checker work of each of these chambers is in communication with suitable air or gas openings, not shown. In the operation of the furnace, air and gas are mixed adjacent the combustion openings 10^h on one side of the furnace, ignited at such openings, and the hot gases travel 100 across the furnace to the openings on the other side through which they exhaust. Thence they travel, as indicated by the arrows in Fig. 2, through the regenerative checker work operating to heat the latter 105 and at the conclusion of a certain period the

air and gas flow is reversed and the previously heated checker-work is traversed by the unburned gases and air which are thereby heated, this structure constituting a regenerative heating apparatus, as is well known to those skilled in the art.

This combustion of air and gas and the travel of the same across the tank furnace results in the efficient melting of the batch, which as it melts, becomes fused and gradually flows toward the opposite end of the furnace. Intermediate the extremities of the furnace are provided abutments 10^a projecting from the side walls 10^a into the furnace, and a series of refractory blocks 11 constituting links of a floating dam or boom extend between the side walls 10^a, a pair of these blocks 11 having their ends abutting against the abutments 10^a and inclined toward the charging end of the furnace. The interfitting end arrangement of the blocks 11 maintains them in a bowed position against the flow of the molten glass, and since these blocks are constructed of suitable refractory material they float on the molten glass, being partially submerged therein. By this construction a small flow of the molten glass operates to maintain the dam, composed of blocks 11, in proper position, as will be obvious. These blocks 11 operate to prevent the flowing of the scum or dross floating on the molten glass, and consequently it will be apparent that impurities carried on the surface of the glass are prevented from flowing toward the discharge end. We have shown a pair of dams constructed of these blocks 11, and it is obvious that this number may be altered, if found desirable.

In the end wall 10^b of the furnace is provided an outlet opening 10^c communicating with a discharge trough 10^d, and an abutment 10^e is located adjacent the discharge opening 10^c and projects into the furnace, as is shown in Fig. 1. A collecting ring or member 13 provided with legs or flanges 13^a is located in the furnace adjacent the discharge opening 10^c, the legs 13^a coacting with one wall of the furnace and the abutment 10^e to maintain the ring in proper position. Inasmuch as the latter is constructed of suitable refractory material of less density than the molten glass it will float on the latter and prevent or substantially prevent flowing of impurities or scum out of the discharge opening 10^c. A gate valve 14 is provided at the communication of the discharge opening 10^c is a trough 10^d, as is shown in Fig. 3, and the same may be raised or lowered to permit, prevent or regulate flow of molten glass from the furnace into the trough 10^d, as will be apparent. This gate 14 is preferably concave on its lower portion to closely fit the bottom of trough 10^d when in closed position. A strap 15 at-

tached to the end wall of the furnace is provided and it extends around the valve 14 to prevent the displacement of the latter from proper position. The block 10^e at the discharge opening 10^c is further provided with the inwardly projecting shoulder at its outer end to prevent sidewise movement of the valve and to assist in holding the same against the flow of molten glass. A threaded rod 16 is attached to the gate valve 14 and extends upwardly therefrom through a pair of apertured lugs 17^a carried by the spaced apart brackets 17 which are attached at the end of the furnace. Between these lugs and threaded on the rod 16 is the hand wheel 19, proper rotation of which will result in raising or lowering of the rod 16 and gate valve 14, as is obvious.

An auxiliary furnace or chamber 20 is provided adjacent the discharge end of the furnace 10, this chamber being formed with side walls 20^a and top wall 20^b. A suitable inlet opening 20^c is provided in one of the side walls 20^a and through this opening projects the trough 10^d, as shown in Fig. 3. Fuel intake and discharge openings 20^d, 20^e, respectively, are provided, the same being in communication with air and gas ducts 20^f, 20^g which lead from suitable regenerative chambers, generally indicated by numeral 20^h. It will be obvious to those skilled in the art that one of the openings 20^d, 20^e will supply and provide for ignition of the fuel, the heated gas traveling therefrom around in the teeming chamber 20 and out the other of openings 20^d, 20^e, the air and gas supply being previously heated by the regenerative chambers.

A collecting saucer or receptacle 21 is mounted in the furnace 20 and constitutes a bottom therefor, this saucer being dished or otherwise hollowed out, as indicated by numeral 21^a, see Fig. 3. This receptacle 21 is preferably constructed, as shown in Fig. 1, with the converging sides 21^b leading to and forming a spout 21^c located beneath the trough 10^d. The collecting saucer 21 is preferably formed of refractory material and is mounted in a cast-iron or other metal shell 22 which is preferably apertured, as indicated by numeral 22^a, to provide for cooling of the saucer and shell. The shell 22 is further provided with transverse ribs 22^b to which is attached a rock shaft 23. This shaft 23 is provided at one end with the worm gear 23^a with which meshes a worm 24 carried on a shaft 25 to which is also secured a hand wheel 26. It will be obvious that rotation of this hand wheel in the proper direction will result in a tilting or partial rotation of the saucer 21 when it is desired to pour from the same.

Located beneath the auxiliary furnace 20, extending some distance to one side thereof, are the tracks 28. A rolling table, gen-

erally indicated by numeral 30, is provided, the same comprising the composite formed table portion 30^a, see Fig. 7, in which are provided water or other cooling fluid ducts 30^b. The table proper 30^a is mounted upon beams 30^c, between which extend the cross beams 30^d forming a rigid and compact structure. Journal boxes 30^e depend from the cross beams. In these are mounted the 16 axles of wheels 32 which roll upon the tracks 28. Cross bars or beams 30^f are also provided in the underside of the table and to these cross beams 30^f is attached a rack 30^g of a length greater than that of the width of 15 the table. Located below the table in the path of movement thereof are the upright pedestals or brackets 33 in which is journaled the shaft 34 of the gear 34, meshing with the rack 30^g. A motor 38 is mounted 20 adjacent the gear 34, this motor being provided with a shaft 37^a upon which is mounted a worm 37, normally meshing with the gear 34, so that proper actuation of the motor 38 will result in the rotation of gear 25 34 and translation of rack 30^g together with the table 30.

We also provide a leir or annealing furnace, generally indicated by numeral 40, the same being provided with a charging opening 40^a adjacent which is provided a stationary table 40^b, see Figs. 1 and 5. At each side of the stationary table 40^b is provided an inclined block 40^c, see Fig. 5. The rolling table 30 may be moved on the tracks 28 to the position shown in Fig. 4, and one end thereof will be adjacent the table 40. Adjacent its other end, when in such position, is the scraper table 50, provided with suitable legs 50^a, shown in Fig. 5. Projecting 40 outwardly from each side of the table 50 and secured thereto, is a track guide 50^b adapted, when in the position shown in Fig. 4 for example, to align with similar tracks 30^b carried by the table 30. A scraper member, 45 generally indicated by numeral 51, normally rests on and is supported by the table 50, as shown in Fig. 5, the latter being provided with an upstanding flange or wall 50^c at its end adjacent the rolling table 30.

50 The scraper 51 comprises a rear cross bar 51^a on which are pivotally mounted collars 51^b. Converging bars 51^c are attached at one end to the cross bar 51^a at one extremity and extend to the scraper blade 51^d at their other extremity. A central bar 51^e is also provided extending between the cross bar 51^a and scraper blade 51^d. Transverse braces 51^f extend between the cross bar 51^a and the bars 51^c. Depending from the cross bar 51^a 55 are the legs 51^g which in turn are mounted upon rollers or wheels 51^h which ride upon tracks 50^b, 30^b, as will be more fully explained. A pressing roller 55 is provided to form the plate, this roller being preferably air or similarly cooled and resting

against blocks or shoes 55^a when not in operation, as shown in Fig. 5. At the sides of the table are provided the spacing or gage strips 55^b, upon which rides the roller 55, the thickness of the plate being determined by these gage strips. When it is desired to roll or press out the molten glass the roller 55 is moved, by means to be hereinafter described, to the position shown in dotted lines therein, partially up the inclined blocks 40^c in which position it may be wedged or otherwise suitably retained to permit the glass plate to be moved from the table. It will be noted that the shaft 23 is substantially parallel to the axis of roller 55. 80

The trough or trench 60 is provided, preferably beneath the stationary table 40^b, see Fig. 5, in which trench are rotatably mounted the shafts 61, 62. Each of these shafts carries a pair of drums or winding pulleys 61^a, 62^a, respectively, and gears 61^b, 62^b, respectively. A driving motor 63 is provided, the same having a suitable shaft 64 to which is attached the gear 65 meshing with a second gear 66 carried on an oscillatable handle 67. This latter may be moved to throw gear 66 into mesh with either gear 61^b or gear 62^b, as will be obvious, see Figs. 4 and 5. Cables or chains 68^a extend from around pulleys 61^a to and over pulleys 61^a 95 mounted in brackets extending from the front of the leir to shackles or thimbles carried by collars 51^b on scraper bar 51^a. Similarly, cables 64^a extend from around pulleys or drums 62^a to and around pulleys 62^a, 100 mounted in brackets extending outwardly from the front of the leir, these last named cables carrying hooks 62^b at their ends which may be slipped over the ends of the shaft of roller 55 between suitable guide 105 disks 55^b, see Fig. 5, when it is desired to move the roller. It is obvious that with these hooks in engagement and the gears in mesh, as shown in Fig. 5, proper rotation of the motor 63 will draw the roller 55 across 110 the table and up on inclined blocks 40^c, as described above. At the completion of this operation, the handle 67 may be swung over to enmesh gear 66 with gear 61^b. Upon further operation of the motor the scraper 50 115 will be drawn across the table 30, the scraper blade 51^d dropping into contact with the table and the plate of glass thereon, as the arms 51^c, 51^d ride forwardly on upstanding flange or wall 50^c, as will be apparent. 120 Movement of this scraper across the table will result in pushing the glass plate thereon off the table on to stationary table 40 and from thence into the leir.

Assuming that the apparatus is in proper 125 position and molten glass is contained in the furnace 10, the operation of our invention is as follows:

The valve 14 is raised whereupon molten glass will flow out through the trough 10^a 130

beneath the collecting ring 13, into the collecting saucer 21 which is of sufficient size to contain a proper charge of molten glass. After sufficient of the molten glass has been drawn off, the valve 14 is moved to closing position cutting off the flow of glass. Heat may then be applied to the chamber 20, if it is desired to settle or clear or further fuse the glass for whatever period may be desirable until the molten glass is of a proper consistency and homogeneity and at the proper temperature for pouring. By utilizing a shallow dish or saucer, of the nature shown and described, the surface exposed to the action of the auxiliary furnace heat is comparatively great in proportion to depth of the glass, so that this settling or clearing may be equably and rapidly performed in contradistinction to the settling of the glass in the ordinary flasks. Furthermore the heat in the auxiliary chamber may be readily regulated, as desired.

When the glass has reached its proper condition in the saucer 21, the rock shaft 23 is operated and the saucer tilted at the desired speed, the table 30 being in the position shown in Fig. 3, for example subadjacent to saucer 21. As the saucer is tilted the molten glass will be delivered close to and partially beneath the roller 55, as indicated in Fig. 3. As the saucer is tilted the table is preferably moved at a uniform rate from beneath the teeming furnace 30 toward the leer, this movement, when regulated in conjunction with the tilting of the saucer 21 by a skilled operator, resulting in the deposit of a uniform ribbon or mass of molten glass close to and partially beneath the roller 55 for the entire width of the table. This simplifies and improves the rolling of the plate which next takes place. The table is moved by means of the motor and rack, described above, to the position shown in Fig. 4, between tables 50 and 40^b, when chains 64^a may be attached to the shaft of the roller 55. Gears 66 are enmeshed with gears 62^b and the motor 63 is actuated to move the roller 55 across the table 30 resulting in the squeezing out of the glass plate to a thickness corresponding to the height of the gage strips 55.

By the use of this apparatus we are enabled to eliminate the greater portion of the labor required in present day practice to distribute and spread the molten glass on the table adjacent the roller, as the arrangement of the saucer with respect to the roller and the movability of the table permit uniform distribution of the molten glass directly beneath the roller and closely adjacent thereto, as explained above.

After the roller is carried across the table it is moved up on the blocks 40^b, as indicated in dotted lines in Fig. 5, in which position it may be retained by wedge blocks

or the like. The gear 66 is then thrown into mesh with gears 61, as described above, and the scraper is moved across the table to push the glass plate therefrom into the leer wherein it may be annealed or further treated.

By the use and practice of our improved apparatus we are enabled to provide and utilize a continuous melting, eliminating the use of the ordinary flasks or pots objectionable on account of their relatively small capacity and their wear and expense and the confusion resulting from their breaking. We also eliminate, to a considerable extent, the labor required at present to turn out plate glass by eliminating the use of the flasks and their consequent handling. In addition, we obtain a more even and consistent product and are enabled to properly settle and treat the molten glass as desired.

It will be apparent that our apparatus provides many other advantages over those now in use, and it will also be apparent that our invention is susceptible of modifications and improvements and we do not wish to be restricted to the form shown and described beyond the scope of the appended claims.

What we claim is:

1. In apparatus for making plate glass, a melting furnace, an auxiliary treating chamber, a collection receptacle located in said chamber thermally independent of said furnace, means to deliver a charge of molten glass from said furnace to said receptacle in said chamber, and means to heat said chamber independently of said furnace.

2. In apparatus for making plate glass, a melting furnace, an auxiliary treating chamber thermally independent of said furnace, a collection receptacle located in said chamber and forming the bottom thereof, means to deliver a charge of molten glass from said furnace to said receptacle, and means to heat said chamber independently of said furnace.

3. In apparatus for making plate glass, a melting furnace, an auxiliary treating chamber thermally independent of said furnace, a collection receptacle located in said chamber, means to deliver a charge of molten glass from said furnace to said receptacle, means to heat said chamber independently of said furnace, and a rolling-table movable to a position subjacent to said collection receptacle, the latter being operable to deposit its charge directly on said table beneath the roller thereof.

4. In apparatus for making plate glass, a melting furnace, an auxiliary treating chamber thermally independent of said furnace, a collection receptacle located in said chamber, means to deliver a charge of molten glass from said furnace to said receptacle, means to heat said chamber independently of said furnace, and a rolling-table movable to a position subjacent to said receptacle,

- the latter being tiltably mounted in said chamber and operable to deposit its charge directly on said table beneath the roller thereof.
5. In combination, a melting furnace, a thermally independent auxiliary treating chamber located adjacent to and spaced from said furnace, means to heat said chamber independently of said furnace, means to transfer a charge of glass directly from said furnace to said chamber, said means comprising a trough or the like, said trough projecting through a wall of said chamber, and a comparatively shallow collection receptacle located in said chamber to receive glass from said trough.
6. In combination, a melting furnace, an auxiliary treating chamber located adjacent to and spaced from and thermally independent of said furnace, means to transfer a charge of glass from said furnace to said chamber, said means comprising a trough or the like, said trough projecting through a wall of said chamber, and a comparatively shallow collection receptacle located in said chamber to receive glass from said trough, said receptacle being tiltably mounted to deliver its contents upon a rolling-table, or the like.
7. In combination, a melting furnace, an auxiliary treating chamber located adjacent to and spaced from and thermally independent of said furnace, means to transfer a charge of glass from said furnace to said chamber, said means comprising a trough or the like, said trough projecting through a wall of said chamber, and a shallow collection receptacle located in and forming the bottom of said auxiliary chamber to receive glass from said trough.
8. In combination, a melting furnace, an auxiliary treating chamber located adjacent to and spaced from and thermally independent of said furnace, means to transfer a charge of glass from said furnace to said chamber, said means comprising a trough or the like, said trough projecting through a wall of said chamber, and a shallow collection receptacle located in and forming the bottom of said auxiliary chamber to receive glass from said furnace to said chamber, said means comprising a trough or the like, said trough projecting through a wall of said chamber, and a shallow collection receptacle located in and forming the bottom of said auxiliary chamber to receive glass from said trough, said receptacle being tiltably mounted to deliver its charge to a rolling-table or the like.
9. In combination, a melting furnace, an auxiliary treating chamber located adjacent to and spaced from and thermally independent of said furnace, means to transfer a charge of glass from said furnace to said chamber, said means comprising a trough or the like, said trough projecting through a wall of said chamber, a comparatively shallow collection receptacle located in said chamber to receive glass from said trough, said receptacle being carried on a rotatable shaft, and means to rotate said shaft to tilt said receptacle.
10. In apparatus for making plate glass, in combination, a melting furnace, an auxiliary treating chamber located adjacent thereto and spaced and thermally independent therefrom, said chamber being provided with a collection receptacle, a leer, and a rolling-table movable from a position adjacent to said receptacle to a position adjacent said leer.

In testimony whereof we have subscribed our names.

JOHN H. McKELVEY.
CHARLES F. RYAN.
